UNITED STATES PATENT OFFICE.

ALBERT SCHMID, OF LONG BEACH, NEW YORK.

CARBURETER.

1,326,000.

Specification of Letters Patent. Patented Dec. 23, 1919.

Application filed June 12, 1918, Serial No. 239,684. Renewed July 22, 1919. Serial No. 312,576.

To all whom it may concern:

Be it known that I, ALBERT SCHMID, a citizen of the United States, and a resident of Long Beach, L. I., New York, have made a new and useful Invention in Carbureters, of which the following is a specification.

This invention relates to charge forming devices for internal combustion engines and more particularly to devices supplemental to the main carbureter for forming combustible charges for starting and during the warming up period.

The use of heavy not readily inflammable liquid fuel such as kerosene and distillates and some of the so called commercial gasolines in internal combustion engines, and especially in engines subject to varying loads makes it important that some means be provided by which readily combustible charges may be supplied during the warming up periods or until the engine becomes warm enough to care for the charges supplied by the main charge forming device or carbureter.

I find that it is impracticable in most cases to heat the main carbureter, either by electricity or other means, sufficiently to form proper charges during the warming up period. An object of this invention is to provide a supplemental or auxiliary starting charge forming device by means of which (during the warming up periods and until the engine is sufficiently warm to be operated upon the main carbureter) readily combustible charges may be supplied independently of the main carbureter.

A further object is to provide an efficient electrically heated device of this character which with a relatively small consumption of electric energy will effectively heat the fuel content of the starting charges in such manner that when the charges reach the engine cylinders they will be readily inflammable and will burn with a minimum of objectionable deposit or smoke.

This as well as other objects, which will readily appear to those skilled in this particular art, I attain by means of the device illustrated in the single sheet of drawings accompanying and forming a part of this application and in which the figure represents in sectional elevation a carbureter embodying this invention.

The device primarily consists of a tortuous passage through which the combustible charges or at least the fuel content thereof,

pass, an electric heater in heat transferring relation to said passage and an agent having relatively great capacity for heat storage and which is in heat transferring relation with reference to said tortuous passage and said electric heater.

The form of device shown in the drawings consists of a tube 2 preferably formed of copper wound around a cylindrical member 3 serving as a passage for exhaust gases from an engine exhaust pipe 4. The inner surface of member 3 is provided with longitudinally extending ribs 5 for the purpose of facilitating the transfer of heat from the hot gases passing through member 3 to the member proper and the tortuous passage.

Member 3 which forms the central channel of the device is preferably made as a part of a base 6 which contains a liquid fuel reservoir and passage 7 adapted to be connected by means of a pipe 8 to any suitable source of liquid fuel supply. The base 6 is also provided with a liquid fuel valve 9 connected by means of passage 10 with reservoir 7 and having its effective area controlled by means of a needle valve 11 of ordinary construction. An air chamber 12 is formed in base member 6 and surrounds the exhaust gas conduit 3. The liquid fuel chamber 7 also surrounds said exhaust gas conduit and because of this the liquid fuel and air passing through chambers 7 and 12 respectively are heated. Air chamber 12 is provided with an inlet 13 and an outlet 14 leading to a point adjacent the outlet of liquid fuel nozzle 9. A valve 15 provided with an enlarged guiding and sealing portion 16 is slidably mounted within a tubular extension 17 of base member 6 arranged axially in line with liquid fuel nozzle 9. Valve 15 controls the flow of liquid fuel through nozzle 9 and its enlargement 16 controls the passage of mixture composed of liquid delivered by nozzle 9 and air passing through chamber 12 to tortuous passage 2 through the connecting channel 18 which connects the inlet of tubular member 17 with said tortuous channel.

Valve 15 is provided with a valve stem 19 operatively connected at 20 to a bell crank 21 under the control of the operator. An electric heater 22 formed in any suitable manner of resistance material spaced and suitably insulated within a heater housing surrounds and contacts with the tubing 11 forming tortuous passage 2.

A cylindrical wall 23 forms a housing sur-

- rounding and spaced apart from the heater element and which extends from the outer margin of base member 6 to a cap member 24 which closes the upper part of the housing. The cap or cover 24 is provided with a lug 25 which forms a support for bell crank 21 and the cap is provided with a passage 26 communicating with the inlet manifold 27 of the engine in connection with which the device is to be used. Outlet 28 of the tortuous passage connects with passage 26. Passage 26 is also provided with an auxiliary air inlet 29 controlled by means of a valve 30 normally held closed by means of a spring 31 surrounding valve stem 19 and positioned between the top of valve 30 and an enlargement 32 at the upper end of the valve stem. The electric heater element through terminals 33 and 34 is connected up to a source of electric energy (here shown as a storage battery 35) and the circuit 36 is controlled by means of a switch 37. The housing of the chamber formed by means of base 6, cylindrical wall 23 and cap 24 and within which the tortuous passage and the heater elements are situated is filled with material 38 and this is preferably a material which has the capacity of storing heat and may either be a solid such as lead or a liquid such as water, although if a vaporizable liquid such as water is used, some means must be provided for the escape of the vapor and replenishment of the liquid, and for that reason a metal such as lead is preferable. This may be poured into the chamber after the elements above described are assembled in place and as it flows around the tube forming the tortuous passage and around the electric heater it is in efficient heat conducting relation to the walls of the exhaust passage 3, the electric heater and the tortuous passage. It will be understood that if sufficient electric current is available this device may be utilized as the main carburetor device of the engine but as the supply of electric current on most automotive devices is limited it is preferable to use this in conjunction with the main carburetor as a starting-charge-forming device and when so used passage 26, that is the outlet passage for the combustible charges, will be connected between the main charge forming device and the engine so that the main charge forming device while this device is in operation may be cut out of operation by means of its throttle valve. In utilizing this device as a starting charge forming device, by closing switch 37 the electric heater will heat the metallic walls of the tortuous passage in a short time sufficiently to render the charges passing through said passage readily combustible and will so superheat them that when they

reach the inlet manifold of the engine in the form of hot vapors they will not be condensed or deposited along the inlet manifold walls.

The electric heater element at the same time it is heating the tortuous passage heats the heat storage material 38 and this material as well as the tortuous passage is in turn heated by the exhaust gases passing through channel 3 as soon as the engine starts to operate and to deliver exhaust gases.

It has been found that by having a sufficient heat storage body in contact with the exhaust passage and the tortuous passage the engine may be readily started after considerable periods of rest without utilizing the electric heater.

As only a small portion of the air enters into the makeup of the mixture traversing the tortuous passage this mixture is readily heated with a minimum of electric energy. In its passage around the helix the centrifugal force tends to throw the particles of liquid against the outer walls of the passage thereby breaking up and vaporizing the fuel.

Having thus described my invention, what I claim is—

1. In a charge forming device for internal combustion engines, a fuel nozzle, a tortuous passage communicating therewith, means for electrically heating said passage, means for passing exhaust gases in heat transferring relation to said passage and a heat storage agent in contact with said passage and said electric heating means. 95
2. In a charge forming device for internal combustion engines, a fuel nozzle, a tortuous passage communicating therewith, means for electrically heating said passage and a heat storage agent in contact with said passage and said electric heating means. 105
3. In a charge forming device for internal combustion engines, a helical passage connected to the engine inlet manifold, means for supplying said passage with fuel, means for passing exhaust gases in heat conducting relation to said passage, a chamber surrounding said passage, an electric heater in said chamber and a heat storage agent within said chamber and in contact with the walls of said passage and said heater. 110
4. In a charge forming device for internal combustion engines, a tortuous tubular passage connected to the engine inlet manifold, means for supplying said passage with fuel, means for passing exhaust gases in heat conducting relation to said passage, a chamber surrounding said passage, an electric heater in said chamber and a heat storage agent within said chamber and in contact with the walls of said passage and said heater. 120
5. A charge forming device for internal combustion engines, comprising means for 125

- 130

- 5 forming relative rich mixtures of liquid fuel and air, a tortuous passage between said means and the engine inlet manifold, an electric heater for said passage, a heat storage agent in heat transferring relation to said passage, and means for passing exhaust gases in heat transferring relation to said passage and to said heat storage agent.
6. A charge forming device for internal combustion engines, comprising means for forming relative rich mixtures of liquid fuel and air, a tortuous passage between said means and the engine inlet manifold, an electric heater for said passage, and a heat storage agent in heat transferring relation to said passage.
7. In a charge forming device for internal combustion engines, a walled passage for exhaust gases, a tube coiled around said passage and having its outlet in communication with the engine inlet manifold, a fuel nozzle communicating with the inlet of said passage, a valve controlling said fuel nozzle and an electric heater in heat transferring relation to said passage.
8. In a charge forming device for internal combustion engines, a walled conduit for exhaust gases, a passage surrounding said conduit and having its outlet in communication with the engine inlet manifold, a fuel nozzle communicating with the inlet of said passage, a valve controlling said fuel nozzle and an electric heater in heat transferring relation to said passage.
9. In a charge forming device for internal combustion engines, a walled passage for exhaust gases, a tube coiled around said passage and having its outlet in communication with the engine inlet manifold, a fuel nozzle communicating with the inlet of said tube, a valve controlling said fuel nozzle, an electric heater and a heat storage agent surrounding said tube and in contact with said passage.
10. In a charge forming device for internal combustion engines, a walled passage for exhaust gases, a helical conduit surrounding said passage and having its outlet in communication with the engine inlet manifold, a fuel nozzle communicating with the inlet of said passage, a valve controlling said fuel nozzle and an electric heater in heat transferring relation to said passage.
11. In combination with a walled passage for conducting exhaust gases from an internal combustion engine, a fuel conduit surrounding said passage, an electric heater surrounding said conduit, a heat storage agent surrounding and in contact with said heater, said conduit and said passage, means including a valve for supplying said conduit with controlled charges of fuel, a supplemental air valve for said device and common means for controlling both of said valves.
12. In a charge forming device for internal combustion engines, a fuel nozzle, a passage communicating therewith, means for electrically heating said passage and a heat storage agent in contact with said passage and said electrical heating means.
13. In a charge-forming device for internal combustion engines, a fuel nozzle, a passage of relatively great length and small cross section communicating therewith, means for electrically heating said passage, a heat storage agent in contact with said passage and said electrical heating means, and means for heating said heat storage agent by exhaust gases.
14. In a charge-forming device for internal combustion engines, a fuel nozzle, a passage of relatively great length and small cross section communicating therewith, means for electrically heating said passage, a heat storage agent in contact with said passage and said electrical heating means, and means for passing exhaust gases in heat transferring relation to said heat storage agent.

In testimony whereof, I have hereunto subscribed my name this 7th day of June, 1918.

ALBERT SCHMID.
